UNITED STATES PATENT OFFICE.

THOMAS WICKHAM, OF HUB CITY, WISCONSIN.

DEVICE FOR CATCHING ANIMALS.

SPECIFICATION forming part of Letters Patent No. 404,583, dated June 4, 1889.

Application filed December 19, 1888. Serial No. 294,036. (Model.)

To all whom it may concern:

Be it known that I, THOMAS WICKHAM, of Henrietta township, (Hub City P. O.) in the county of Richland and State of Wisconsin, have invented a new and Improved Animal-Catcher, of which the following is a full, clear, and exact description.

The object of the invention is to provide a new and improved animal-catcher, specially adapted for catching hogs, sheep, &c., by the leg.

The invention consists in a frame, a segmental arm fulcrumed on the said frame and actuated by a spring, and a band secured to the said frame and the said segmental arm.

The invention also consists in certain parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a plan view of the improvement in an open position. Fig. 2 is a side elevation of the same in a closed position, and Fig. 3 is a sectional end view of the same on the lines *x x* of Fig. 1.

The improved animal-catcher is provided with a frame A, having a bottom plate B cut away in its front edge at B', and provided on one end with an upwardly-extending arm B², in which and the bottom plate B is mounted to turn a shaft C, carrying on its lower end an outwardly-extending arm D, on the outer end of which is formed a segmental arm E, having teeth E' cut in its front edge, as is plainly shown in Fig. 1. The outer free end of the segmental arm E is connected with one end of a band F, preferably of leather, connected at its other end to the inner end of a U-shaped arm B³, secured on the top of the bottom plate B opposite the arm B². The segmental arm E is so arranged that when in a closed position it passes into and through the U-shaped arm B³, as is plainly shown in dotted lines in Fig. 1.

On the upper end of the shaft C, outside of the arm B², is secured a tripping-arm G, engaging at one end a notched end of the tripping-lever H, fulcrumed at H' on the arm B²,

and extending at its other end above and in front of the cut-out part B' of the bottom plate B. The other end G' of the tripping-arm G is adapted to engage the pin I', formed on a plate I, secured to the outer end of a handle J. In the plate I, on one edge, is also formed a notch I², engaging the shank of a pin I³, secured on the arm B², as is plainly shown in the drawings. The plate I, with its handle J, is thus made detachable from the arm B², and is provided with a notch I⁴, fitting over the shaft C next to the tripping-arm G.

A coiled spring K is coiled on the shaft C and secured by one end to a collar C', secured on the said shaft directly under the arm B². The other end of the said spring K is fastened to the bottom plate B, as is plainly shown in Fig. 2. The spring K has the tendency to throw the lever D and its segmental arm E in the direction of the arrow a', so that the segmental arm E passes into the U-shaped arm B³, as illustrated in dotted lines in Fig. 1. The teeth E' on the segmental arm E are adapted to be engaged by a pawl L, fulcrumed on the bottom plate B, and the middle part of the U-shaped arm B³. The pawl L is pressed in contact with the teeth E' of the segmental arm E by a spring N, held on the said pawl L, its free end pressing against the arm B³. A ring O is secured to the arm B³ and carries one end of a rope P, of suitable length.

The operation is as follows: When the operator desires to set the animal-catcher, he throws the segmental arm E outward into the position shown in Fig. 1, so that the coiled spring K is placed under heavy tension. At the same time the tripping-arm G is moved into the position shown in Fig. 1 by the turning of the shaft C, so that the notched end of the tripping-lever H engages one end of the said tripping-arm G, thereby locking the shaft C, the arm D, and the segmental arm E into place. The end G' of the tripping-arm G rests against the pin I' of the plate I, so that the latter is held in place on the arm B² of the frame A. When the operator now desires to catch an animal—such as a hog or sheep—he takes hold of the handle J and quickly moves the frame A forward, so that the outer end of the tripping-lever H strikes against

the animal's leg above the ankle, whereby the said lever II is disengaged at its notched end from the end of the tripping-arm G. The tension of the coiled spring K now exerts its power and turns the shaft C, so that the arm D and the segmental arm E swing in the direction of the arrow a', whereby the band F is thrown around the leg of the animal and the segmental arm E is locked in place by one of its teeth E' engaging the pawl L, as is plainly illustrated in Fig. 1. The animal's leg is thus secured, and the handle J, with its plate I, becomes detached from the arm B² as the pin I' is disengaged from the end G' of the tripping-arm G. The operator has hold of the free end of the rope P, and thereby holds the animal, the handle J being entirely removed. When the operator desires to release the catcher from the animal's leg, he presses the outer end of the pawl L inward, so as to disengage the pawl from the teeth E' of the segmental arm E, and the latter can again be swung outward into the position shown in Fig. 1. Thus it will be seen that with my improved device an animal can be very quickly caught by the leg without injury.

Having thus described my invention, what I claim as new, and desire to secure by Letters Patent, is—

1. In an animal-catcher, the combination, with a frame, of a segmental arm fulcrumed on the said frame and actuated by a spring, and a band secured to the said frame and the said segmental arm, substantially as shown and described.

2. In an animal-catcher, the combination, with a frame, of a segmental arm fulcrumed on the said frame and actuated by a spring, a band secured on the said segmental arm and the said frame, and a tripping device for locking the said segmental arm in an open position, substantially as shown and described.

3. In an animal-catcher, the combination, with a frame, of a segmental toothed arm fulcrumed on the said frame and actuated by a spring, a band secured to the said frame and the said segmental arm, and a spring-pawl fulcrumed on the said frame and adapted to engage the said toothed segmental arm, substantially as shown and described.

4. In an animal-catcher, the combination, with a frame, of a segmental toothed arm fulcrumed on the said frame and actuated by a spring, a band secured to the said frame and the said segmental arm, a spring-pawl fulcrumed on the said frame and adapted to engage the said toothed segmental arm, and a rope connected with one end of the said frame, substantially as shown and described. 60

5. In an animal-catcher, the combination, with a frame, of a segmental toothed arm fulcrumed on the said frame and actuated by a spring, a band secured on the said segmental arm and the said frame, a spring-pawl fulcrumed on the said frame and adapted to engage the said toothed segmental arm, and a handle for holding the said frame and adapted to be detached, substantially as shown and described. 65

6. In an animal-catcher, the combination, with a frame and a handle held on the said frame and adapted to be detached, of a shaft mounted to turn in the said frame and actuated by a spring, a tripping-arm held on the said shaft and adapted to hold the said handle in place, a tripping-lever fulcrumed on the said frame and engaged by the said tripping-arm, a segmental arm held on the said shaft, and a band secured to the said segmental arm and the said frame, substantially as shown and described. 70

7. In an animal-catcher, the combination, with a frame and a handle held on the said frame and adapted to be detached, of a shaft mounted to turn in the said frame and actuated by a spring, a tripping-arm held on the said shaft and adapted to hold the said handle in place, a tripping-lever fulcrumed on the said frame and engaged by the said tripping-arm, a segmental arm held on the said shaft, and a band secured to the said segmental arm and the said frame, and a spring-pawl fulcrumed on the said frame and adapted to engage notches in the said segmental arm, substantially as shown and described. 80 85 90 95
